[57] ABSTRACT

A ski made of plastic or metal and has a core of highly flexible preferably fibrous material.

SKI

In the past, laminated skis have been developed containing one or several core layers and/or an upper surface portion consisting of tough organic or vegetable elements, or fibrous material, in natural or synthetic form either extending over the full length and/or width of the ski or over part of its length (German Patent Specification No. 527,360). Moreover, a ski is known (German Patent Specification No. 811,328) consisting of wooden veneers of layers laminated together with a layer of resilient material different from wood having a high tensile strength interposed between the wooden layers or veneers. Said layer extends over the whole length and width of the ski and is positioned close to the running surface, preferably on top of it.

The above constructions suffer from the disadvantage that the reinforcing elements have great stiffness in the longitudinal direction but not in the transverse direction as required in modern skiing technique.

In the past it has been tried to construct a flexible ski with bar type steel reinforcing elements in both tension zones extending longitudinally over the whole length, and in which two sets of steel inlays forming one element and extending over the whole length of the ski serve as reinforcement, with the steel inlays of the first set running straight in a longitudinal direction in known manner and those of the second set in a zig-zag pattern over the total length of the ski, thus alternately crossing the longitudinal reinforcement in pairs (German Patent Specification No. 1,578,697). In this case, the steel inlays run in "tension channels" with a certain clearance within the ski and are guided laterally and secured at the ends of the ski. In view of the fact that the flexible wires serving as reinforcements must be run through several eyes and finally tensioned, the labor costs are considerable and cannot be reduced since this design does not allow a mechanization of the production process. Furthermore, friction occurs between the highly resilient reinforcing wire and the lateral deflection points or profile edges. Thus, also in this case, the ski lacks from sufficient stiffness in the transverse direction since under normal conditions, i.e., when skiing on normal slopes, the longer steel elements of the zig-zag type reinforcement are not under tension and can even be in a relaxed condition.

An object of this invention is to produce a ski combining the stiffness in the longitudinal direction of conventional skis with a considerably greater stiffness in the transverse direction as compared to known designs. In other words, a ski is to be provided which is resistant to torsional forces, thus ensuring a high amount of grip. Moreover, it is intended to reduce the weight of the ski to a minimum.

In general, this object is obtained by using fibrous material for the reinforcing elements having a high specific stiffness (modulus of elasticity/specific weight ratio) which is wound about a core and cured after resin impregnation, or pre-treated and cured matted fibrous material with the threads wound at an angle of approximately 30° to 60°, preferably 45°, to the longitudinal axis of the ski in a criss-cross pattern over the width of the ski.

The advantage of this invention consists in that the material properties (modulus of elasticity E, transverse stiffness G) of a fiber reinforced material of great specific stiffness and strength can be utilized by wrapping the threads at the proposed angle between approxi-

mately 30° to 60°, preferably 45°, to the longitudinal axis thus ensuring an amount of flexibility in the longitudinal direction comparable to known plastic and metal skis but a much greater transverse stiffness.

5 It is found that a reduction of the filament angle results in an increase in the modulus of elasticity (corresponding to the bending stiffness) and at the same time in a reduction of the transverse stiffness. With a filament angle of 30° (20°) the transverse stiffness is reduced by about one-third (two-thirds) of the maximum value obtained at 45°.

In view of the fact that at greater filament angles, the stiffness shows an asymptotic characteristic, a limitation to an angle of approximately 60° seems to be necessary, all the more since at this angle the transverse stiffness is also reduced to approximately one third of it maximum.

A ski of the above design offers a transverse stiffness never obtained before without requiring reinforcement ribs or similar features impairing the flexibility and increasing the risk of failure.

An advantageous embodiment of this invention is the use of infinitely long, approximately 1 - 2 km, threads for the core with high specific stiffness and a thermal 25 expansion coefficient approximately constant in the longitudinal direction, which are treated with resin, wrapped around a core member and then cured to form a flat hollow body positioned approximately in the neutral zone and extending over the whole length and 30 width of the ski. Said hollow core can be formed in the following manner: An infinitely long resin-impregnated strand of unidirectional fiber threads is wrapped about a core of constant section, e.g., a form-retaining metal strip, preferably at an angle of 45° to the longitudinal axis; the side surfaces of the hollow body should form a maximum radius because of the high specific stiffness. Subsequently, the resin is cured at the minimum 35 permissible temperature, in the case of epoxy resins 120°, and the metal strip is then removed from the hollow body at an extremely low temperature; this is possible because the radial dimensions of the core remain 40 constant whereas the metal strip is subject to large shrinkage due to great thermal expansion coefficient.

45 Another embodiment of this invention comprises a core of cellular material, e.g., polyurethane foam or a wooden core of any desired section which can preferably be adapted to the section of the ski. In this case, the core cannot be removed after the wrapping operation.

50 According to this invention, the resulting flat and laminated hollow body forms the reinforcing element of the ski which shows a great resistance to torsion, of great transverse stiffness and allows easy control of the longitudinal stiffness by adjusting the height of the hollow body accordingly. Thus, the characteristics of the ski can be varied from great flexibility as obtained by a core roughly corresponding to the sectional height of the ski. A significant advantage lies in the fact that both the ski of high flexibility and of low flexibility offers great transverse stiffness. Said hollow reinforcing core can advantageously be positioned in the neutral zone of the ski since the stiffness is ensured by the configuration of the core.

55 In accordance with another feature of this invention, resin-impregnated matted fibrous material can be provided in one or several planes of the ski with the indi-

vidual threads also positioned at an angle of 30° to 60°, preferably 45°, to the longitudinal axis of the ski and in a criss-cross pattern.

In view of the fact that the fibrous material is also commercially available in short length, this invention additionally provides the use of individual short filaments embedded in a resin matrix instead of a hollow body or matted material.

According to this invention, carbon or boron fibers are used; an outstanding feature of said fibers is their high specific modulus of elasticity or stiffness, i.e., the ratio between modulus of elasticity and specific weight ρ . These fibers are preferably embedded in synthetic resins, in particular epoxy resin. Steel has a specific stiffness $E/\rho \sim 2,500$ km, aluminium $E/\rho \sim 2,600$ km, and glass fibre reinforced plastic (60 percent glass) $E/\rho \sim 2,300$ km, whereas, in the case of carbon fiber reinforced plastic (60 percent C fibers) the means value of $E/\rho \sim$ is approximately 13,000 km, which is comparable to the specific stiffness of boron fibres. The ratio between tensile strength σ_s and specific weight ρ of resin reinforced by carbon or boron fibers is also higher than that of other known materials.

Moreover, reinforcing elements are provided in the transverse and/or longitudinal direction of equal or different thickness where the thickness is selected according to the desired flexibility of the ski. In another embodiment of this invention, on one or on either side of the reinforcing elements of high specific stiffness are used in the longitudinal direction of the ski reinforcing elements of higher flexibility, preferably of glass fiber reinforced plastic, forming the top and/or bottom surface portion of the ski. This arrangement is advantageous when the shell of the ski is to be of glass fiber reinforced plastic.

According to this invention, a ski is obtained having great transverse stiffness over its whole length, and in addition, its flexibility can be controlled as desired during manufacture by different filament angles and, moreover, the ski of this invention will retain its excellent material properties over a longer period than skis of known design. The manufacture of this ski can be largely mechanized so that the customer can be offered a reasonable priced high-performance ski even with higher material costs.

The means by which the objects of this invention are obtained are described more fully with reference to the accompanying drawings, in which

FIG. 1 is a plan view of the ski, partly shown in section;

FIGS. 2, 3 and 4 are, respectively, cross-sectional views taken on the lines II-II, III-III and IV-IV in FIG. 1; and

FIG. 5 is a cross-sectional view through a modification of the ski.

FIG. 6 is a cross-sectional view through a further modification of the ski.

As shown, a ski S has the top surface removed from its tail portion so that unidirectional carbon fibers 1 and 2 are visible embedded in a layer of epoxy resin in a criss-cross pattern at an angle α of 45° to the ski longi-

tudinal axis.

FIG. 2 is a cross-sectional view of the ski taken near the tip portion. The inner zone takes up an extremely flat hollow body 3 consisting of resin-impregnated carbon fibers, in this case, wrapped about a core 4 of polyurethane and extending over the whole width and length of the ski. Shell 5 encapsulating the hollow body consists of glass fibers reinforced resin and is bonded to the core. A groove 6 is in the running surface.

FIG. 3 is a cross-sectional view of the center portion. The height of the laminated hollow body corresponds to the sectional thickness of the ski as can also be seen from FIG. 4, which is a cross-sectional view of the ski tail portion. The hollow body is again of extremely flat configuration.

It should be noted that the height and width of the cross-sectional views shown do not reflect the actual dimensional relationship and that the waist of the ski has not been shown.

FIG. 5 is a cross-sectional view of another embodiment of the ski according to this invention. In this case, carbon fibers, embedded in a resin matrix 7a, 7b, 7c are provided in three planes with two layers of polyurethane foam 8 in between. The side surfaces and the top and bottom surfaces 9 and 9a consist of resin reinforced by glass fiber.

In the embodiments shown, the running edges are indicated by grooves 10 and the running surface represented only by a line 11; the two items are bonded to the bottom surface portion.

As already indicated, this invention is not limited to the embodiments shown, but may include a number of other embodiments which can also be a combination of the embodiments shown; as an example, the carbon fiber reinforced layers 7a, 7b, 7c might be so connected at their side edges that an S-type section is formed or the foam material of layers 8 might be replaced by glass fibers reinforced resin.

Having now described the means by which the objects of this invention are obtained,

We claim:

1. A torsion-resistant, longitudinally elastic plastic ski having an elongated insert including fibers extending transversely to the length of the ski, said insert comprising a preimpregnated and hardened fiber compound layers of fiber-reinforced plastic material whose strands extend at an angle of from 30° to 60° transversely to the length of the ski, said layers being connected along the edges of the insert adjacent the edges in such a way that they form an S in cross-section.

2. The ski of claim 1 in which short fibers are included in the layers.

3. The ski as in claim 1 in which at least one side of the insert, less rigid, striplike inserts, preferably of glass-fiber-reinforced plastic are placed in longitudinal direction of the ski.

4. The ski of claim 3 in which the less rigid materials form the upper and lower outer portions of the ski.

5. The ski of claim 1, in which cellular material is positioned between the layers of the insert.
